UNITED STATES PATENT OFFICE.

EMORY STOCKWELL, OF STAMFORD, CONNECTICUT, ASSIGNOR TO THE YALE
& TOWNE MANUFACTURING COMPANY, OF SAME PLACE.

SAFE-DOOR.

SPECIFICATION forming part of Letters Patent No. 296,643, dated April 8, 1884.

Application filed February 27, 1883. (No model.)

To all whom it may concern:

Be it known that I, EMORY STOCKWELL, of Stamford, in the county of Fairfield and State of Connecticut, have invented certain new and 5 useful Improvements in Safe and Vault Doors, of which the following is a specification.

The object of my invention is to simplify, cheapen, strengthen, and otherwise materially improve the construction of safe or vault doors.

10 Heretofore it has been customary to cast the flanges or frames of safe-doors in one piece, and to secure the front plate of the door thereto. In the style of safes where the bolts and lock are placed back of the filling, a curb or recess 15 is usually formed in the rear face of the door for the reception of the lock and bolt-work. This structure has heretofore been composed of several plates suitably secured to the flanges or frame of the door. This method of manu- 20 facture involves the making of a number of separate pieces, and the subsequent labor of fastening them together, and, among other de- 25 fects, the construction leaves the side flanges, which are preferably thin, insufficiently sup- ported against lateral strain. With the ordi- 30 nary construction, also, it is not practicable to so fill the door that the inside plate will rest against the filling, which is therefore not prop- erly held in place. Under these circumstances 35 it is liable to flake off and to interfere with the proper working of the bolt-work and the lock. The wet filling, which is ordinarily used for such doors, swells more or less, and is liable to cause the flanges or frame to spring outward and distort or burst the door.

40 My invention consists, first, in casting the door frame or flanges and the curb or recess, which is also the bolt-supporting plate, in one piece; and, second, in extending the casting entirely across the door-frame, so as to firmly 45 brace and strengthen it.

The advantages of my improvements are, the reduction in the cost of manufacture by de- 50 creasing the number of parts, and the corre- 55 sponding diminution of the labor of assembling them. The strength of the door is greatly increased, as the bolt-supporting plate or curb extends from flange to flange across the door and braces them against lateral strains, caused

50 by the swelling of the filling or otherwise, and the flaking off or sifting out of the filling, which would not only be injurious to the working of the lock, but would impair its own integrity, is prevented. The security of the safe is also increased, and as the lock and bolts are 55 attached to a part of the frame itself, they cannot so readily be driven off as where the bolt-supporting plate is a separate piece.

55 In the accompanying drawings, Figure 1 is a plan view of the inside of my improved safe-door. Fig. 2 is a section on the line 22 of Fig. 1; Fig. 3, a plan view of the inside of a door, partly broken away to show parts beneath the surface; and Fig. 4 is a section on the line 44 of Fig. 3.

60 The frame or flanges of the door A and the curb or recessed bolt-supporting plate B are cast in one piece, preferably of the general con- 65 tour illustrated in Fig. 3 of the drawings—that is, with the elongated vertical chamber or re- 70 cess F' near the edge of the door for the re- ception of the bolts F and carrying-bar G, and a lateral recess or extension, B', in said cham- 75 ber, in which the tongue H of the bolt-work and the dogging devices are placed. The sides C' 80 of the curb or recess B' preferably constitute guides for the bearing-arms C² C², which project laterally from the tongue H of the bolt- 85 work. The throw of the bolt-work is limited by stops C on the tongue of the bolt-work, and the bolt-supporting plate or bottom of the curb.

90 D' represent the sleeves of the bolt-work and lock-spindles, and E the independently- attached front plate of the door. The web or brace b extends from the curb to the opposite side of the framing, and forms a part of the same casting. The curb for the bolt-work and lock is sunken within the rear face of the door, so that the filling can come up flush with the inside of the plate and curb, and the inside 95 plate of the door can be placed over them and bear firmly against the filling at all points, thus giving the greatest attainable thickness of filling, and consequent security against fire.

I prefer to make the curb and cross-brace or 95 supporting-plate of the shape illustrated in the drawings, because it is more economical and at the same time gives ample strength. It is

obvious, however, that while such a construction possesses material advantages, it is not a necessary accompaniment of my invention.

I do not claim a safe-door casting having the flanges of the lock-plate cast together in one piece, the plate being formed with a curb to receive the lock and bolt-work.

I claim as my invention—

1. The combination, substantially as set forth, of the door-flanges and the plate cast in one piece therewith, the plate being provided with a lock-curb and stops, and guides for the bolt-work, the whole being so arranged that the filling of the door may be flush with the inside of said plate and curb.

2. The combination, substantially as set forth, of the frame or flanges, the plate cast in one piece therewith, and provided with a curb or recess for the reception of the lock and bolt-work, and the brace or reduced portion of the casting *b*, which extends from the curb to the opposite flange of the door-frame.

In testimony whereof I have hereunto subscribed my name this 29th day of January, A. D. 1883.

EMORY STOCKWELL.
